Application September 6, 1938, Serial No. 228,469

8 Claims. (Cl. 12—142)

This invention relates to methods for use in the manufacture of shoes and is illustrated herein with reference to shoes having outsoles which extend only a short distance rearwardly of the heel breast lines of the shoes.

Outsoles of the type referred to are frequently attached to the shoes by pyroxylin cement in a sole attaching press, the cement being first applied to the outsole and overlusted shoe upper and allowed to dry. Just before the sole attaching pressure is applied the cement is activated by a solvent to put it in condition for sticking the sole to the shoe bottom. Since outsoles of the present type do not overlap the entire heel seat portion of the shoe bottom it is especially difficult, particularly in presses having no sole and shoe positioning mechanism, to position the sole and shoe relatively to each other in the press after the solvent has been applied.

An object of the present invention is to provide an improved method of making shoes which may be practised by hand or with the aid of a machine of the type disclosed herein.

To the accomplishment of this object the invention provides in accordance with one feature an improved method of making shoes having short outsoles of the type referred to which comprises locating a fastening member between an outsole and a shoe bottom, positioning the cutsole and shoe relatively to each other, and while maintaining them in such positions, pressing the fastening member into fastening engagement with the outsole and shoe thereby to establish the relative positions of the outsole and shoe so that they may, if desired, be moved relatively to each other prior to the attachment of the outsole without losing such positions. The method further provides in the case of shoes having cement attached outsoles for activating sole attaching cement on the outsole and shoe bottom by raising the outsole with the aid of the fastening member to apply solvent to the cement and for returning the outsole to its established position so that sole attaching pressure may be applied to attach the outsole permanently to the shoe bottom.

With the above and other objects and features in view, the invention will now be described in connection with the accompanying drawings and will thereafter be pointed out in the claims.

In the drawings,

Fig. 1 is a side elevation of a machine with the aid of which the present invention may be prac-

tised, parts of the machine being broken away and a sole and shoe being shown as mounted therein;

Fig. 2 is a plan view of the machine with its operating instrumentalities shown in their operative positions by full lines and in their inoperative positions by broken lines;

Fig. 3 is an enlarged plan view similar to Fig. 2 but with upper portions of the mechanism removed;

Fig. 4 is an enlarged detail view, partly in section, of the sole positioning gage of the machine;

Fig. 5 is a side elevation, partly in section, of the sole and shoe positioning gages of the machine with the shoe gages positioning the shoe;

Fig. 6 is a view similar to Fig. 5 after the sole gage has positioned a sole on the shoe and the driver of the machine has been operated;

Fig. 7 is an enlarged transverse sectional view taken on the line VII—VII of Fig. 6;

Fig. 8 is a detail view partly in section of a portion of the driver operating mechanism of the machine;

Fig. 9 is a bottom plan view, partly in section, illustrating the rear ends of the shoe gages and the mechanism for operating the gages as seen from below;

Fig. 10 is a perspective view of a hinged fastening member which is utilized with the present machine in practising the invention;

Fig. 11 is a perspective view showing the outsole raised by an operator from the shoe bottom with the aid of the hinged member to permit the operator to apply solvent to cement on the outsole and shoe bottom;

Fig. 12 shows the sole and shoe mounted in a sole attaching press in which the outsole may be cement attached to the shoe bottom; and

Fig. 13 is an enlarged side elevation, partly in section, of the heel portion of the shoe after a heel adapted to interengage when the rear portion of the outsole has been attached to the shoe.

The present machine, which is especially adapted for practising the method disclosed herein, comprises a horizontal base 20 upon which is secured by screws 22 a supporting plate 24. Near its forward or right-hand end, as viewed in Fig. 1, the supporting plate 24 has secured thereto a transverse guide plate 26 secured by screws 28. Extending vertically through slots in the base 20 and the plates 24, 26 is a bar 30 the upper end of which is en-

55

larged and provided with a wedge-shaped guideway 32 extending widthwise of the plate 24. Mounted for sliding movement in the guideway 32 is a slide member 34 provided with a T-shaped guideway 36 extending longitudinally of the machine or at right angles to the guideway 32. Slidably mounted in the guideway 36 is a second slide member 38 which carries a last pin 40 arranged to enter somewhat loosely a thimble 42 which forms the hole in the heel end of a last 44, as shown in Fig. 1. The arrangement of the last support is such that the last pin 40 may be adjusted longitudinally for lasts of different lengths and also transversely of the machine for lasts for right and left shoes, the friction between the parts serving to maintain them in adjusted position.

At its lower end the bar 30 is pivotally connected by a pin 46 to ears 48 formed on the upper end of a threaded rod 50. Secured by screws 52 to the under side of the base 20 is a U-shaped bracket 54 which extends downwardly at opposite sides of the bar 30 and has a cross portion 56 through which the rod 50 is threaded. By this means the last support 38, 40 may be adjusted into different heightwise positions for lasts of different sizes, a pair of nuts 58 being threaded on the rod 50 to secure it in adjusted position.

Pivoted on a stud screw 60, vertically mounted in the plates 20, 24 forwardly of the last support 38, is a curved arm 62 having a horizontal portion projecting outwardly beyond the plate 24. Adjustably mounted on the horizontal arm 62 is a toe rest 64 which is secured to the arm by a set screw 66 and has an upper end shaped to engage the toe portion of a shoe, as shown in Fig. 1. The arm 62 may be swung about the vertical screw 60 into any desired lateral position relatively to the supporting plate 24 and, consequently, may be positioned to engage the toe ends of either right or left shoes. For operating on shoes of different lengths the toe rest may be adjusted along the arm 62 and secured in position by the set screw 66.

It is desired that the shoes and soles which are to be relatively positioned by the illustrated machine be located in a predetermined position lengthwise of the machine in order that the shoe and sole positioning mechanism may operate properly thereon and also in order that mechanism with which the machine is provided for forcing or pressing a fastening into the sole and shoe will be located in a position to engage the fastening. To insure that each last which is mounted on the heel pin 40 and toe rest 64 will be located in a predetermined lengthwise position in the machine irrespective of the length of the last, an abutment 68 is provided for engaging the heel end of the last, the abutment being carried on the end of an upwardly curved arm 70 formed on a substantially horizontal plate 72 which, in turn, is pivotally mounted on a pin 74 for swinging movement lengthwise of the machine, the pin 74 being carried in upstanding ears on a pair of brackets 76 secured by screws 78 to the supporting plate 24. The plate 72 is urged normally in a counterclockwise direction about the pivot 74 by a compression spring 80 mounted between the forward end of the plate 72 and the supporting plate 24, the limit of swinging movement of the plate 72 being controlled by a stop screw 82 threaded into the rear end of the plate and engaging the plate 24. Accordingly, the longitudinal position of the heel abutment 68

may be varied at will by adjusting the stop screw 82.

Secured to the supporting plate 24 by screws 84 is an upstanding bracket 84 which straddles the pivoted plate 72 and, at its upper end, is provided with two arms 86 (Figs. 1 and 9) having horizontal projections 90 formed thereon. Secured by screws 92 to the projections 90 is a plate 94 of substantial thickness which extends rearwardly of the bracket 84 for a considerable distance. At its rear end the plate 94 is supported by a strap 96 secured thereto by screws 98 (Figs. 1 and 9) and secured at its lower end to the plate 24 by screws 100. Mounted for pivotal movement on the plate 94 somewhat rearwardly of the bracket 84 is a bracket 102 having a circular base portion 104 provided with a cylindrical projection 106 (Fig. 1) extending downwardly therefrom, the projection 106 extending through a hole formed in the plate 94 and being rotatable in the hole. The bracket 102 is maintained on the plate 94 by a screw 110 threaded into the cylindrical projection 106, this screw also holding against the end of the projection 106, but on the lower side of the plate 94, a cam member 112 (Figs. 1 and 9). The arrangement of these parts is such that the cam member is fastened by the screw 110 rigidly against the projection 106 but is rotatable with the bracket 102 relatively to the plate 94.

The bracket 102 has a forwardly projecting horizontal arm 114 which is enlarged at its forward end 116 and is provided with a vertical slot 118 closed by a cover plate 120. Mounted for reciprocating movement in the slot 118 is a bar member 122 which is slotted at its intermediate portion to receive a compression spring 124 for normally maintaining the bar at the upper limit of its vertical movement, the spring bearing at its upper end against the bar and at its lower end bearing against a projection 126 extending into the opening in the bar from the end portion 116 of the arm 114. The upper limit of the movement of the bar is determined by the latter abutting against the projection 126. The bar 122 forms means for pressing or driving the fastening member referred to into the outsole and shoe bottom.

The bracket 102 is provided with two upstanding ears 128 between which is pivotally mounted on a pin 130 a lever 132. The lever 132 has a forwardly projecting arm carrying a roll 134 mounted on a pin 136 and arranged to engage the upper end of the bar or driver member 122 and depress it against the spring 124 to force the fastening member into the shoe and sole, as will be later described. The lever 132 has a rearwardly extending arm 138 provided on its end with a roll 140 pivoted on a pin 142. The weight of the arm 138 is sufficient normally to maintain the driving lever in an inoperative position with the roll 134 located above the end of the driver bar 122, as shown in Fig. 1, this position being maintained by stop screw 144 mounted in the bracket 102.

It will be seen from the foregoing that the bracket 102, the cam 112, the driver bar 122, and the lever 132 may all be swung relatively to the horizontal plate 94 about the axis of the cylindrical projection 106. This mechanism is swung from an inoperative position shown in broken lines in Fig. 2 to an operative position shown in Figs. 1 and 2, this latter position being determined by a stop 146 mounted in the plate 94. When the driver bar, driving lever, and associ-

ated mechanism are located in the position shown in Fig. 1, the lever is in position to be operated upon by mechanism arranged to engage the roll 140 and swing the lever 132 about its pivot 130 to actuate the bar 122.

The mechanism for actuating the lever 132 comprises an upstanding plate or bar 150 extending through slots in the plates 20, 24 and 94 and provided at its upper end with a horizontal surface 152 (Fig. 8) for engaging the roll 140. A shoulder 154 is provided on the surface 152 by a projection 156 to insure that the bar 150 will not act upon the roll 140 unless the latter has been swung fully into operative position against the stop 148. The projection 156 on the bar 150 is arranged to engage the plate 94 and thus determine the lower position of the bar. At its lower end the bar 150 is pivotally connected by a pin 158 to a treadle rod 160 the lower end of which is connected by a pin 162 to a treadle 164 pivoted on a pin 166 mounted in a treadle support 168. Depression of the treadle 164 elevates the bar 150 to bring the surface 152 into engagement with the roll 140 thereby rotating the lever 132 and causing the member 122 to descend and drive the fastening member into the sole and shoe bottom. The weight of the parts 150, 160 normally maintains the treadle 164 in its elevated position.

The horizontal plate 94 is provided on its upper side with a slot 170 (Figs. 1 and 2) which extends lengthwise of the plate and in which is mounted for movement toward and from the shoe a slide 172. Adjacent to its rear end the slide 172 has pivotally connected to it by a screw 174 a rod 176 which extends upwardly at an angle and at its upper end is secured to the pivot pin 130. Consequently, when the bracket 102 and its associated mechanism, including the lever 132, are swung about the axis of the projection 106 from its inoperative to its operative position, the slide 172 is moved positively toward the shoe and, when the bracket 102 is swung in the opposite direction, the slide 172 is moved positively away from the shoe. At its forward end the slide 172 has adjustably secured to it by slot and screw arrangements 178 (Figs 3 and 4) a horizontal plate 180 to the forward end of which is pivoted by a pin 182 a sole gage 184. As best shown in Figs. 3 to 6, inclusive, the sole gage 184 is provided with two forwardly projecting ears 186 adapted to enter corresponding slots 250 (Fig. 11) formed in the rear portion of a short outsole A, that is, a sole which terminates a short distance rearwardly of the heel breast line of the shoe. The upper portion of the sole gage 184 comprises a substantially horizontal plate arranged to extend over the rear portion of the sole engaged by the underlying projections 186 and thereby to prevent the sole from lifting out of engagement with the projections. Secured by a screw 188 (Fig. 1) to a solid portion of the bracket 84 is a wire spring 190 which extends forwardly through an opening in the bracket and has a curled end arranged to engage the sole gage 184 when the slide 172 is retracted from the shoe and to hold the gage in an upwardly inclined position, as shown in Fig. 5. When the slide 172 is moved forwardly into its operative position, the spring 190 is depressed by the slide to permit the gage to swing downwardly against the shoe bottom, thereby locating the projections 186 in a position in which the slots 250 in the outsole A may be brought into engagement therewith and thereby locate the outsole relatively to the shoe bottom. Before the outsole is placed on the shoe bottom in the posi-

tion determined by the shoe gage 184, the shoe itself is positioned transversely of the machine on the shoe supporting member 40 and the toe rest 64, it being understood that while these members support the shoe in substantially the proper position for receiving the sole, they do not position it in exactly the desired position relatively to the sole because the adjustments for right and left shoes have been manual adjustments which are not accurate and also because the last pin 40 is preferably somewhat loose in the last thimble 42 so that the last itself is capable of some lateral or tipping movement relatively to the pin to enable the heel end of the shoe to be brought into proper alignment with the rear portion of the outsole.

The mechanism for positioning the rear portion of the shoe B on the supporting members 40 and 64 comprises a pair of gages 192 (Figs. 1, 3 and 9) pivoted for equal and opposite movement toward and away from the shoe on screws 194 secured to the under side of the plate 94. Rearwardly of the pivots 194 the gages 192 have arms 196 between which extends a tension spring 198 secured to each arm by a pin 200 and tending normally to hold the forward ends of the gages 192 in their open or retracted position. The arms 196 have curved inner surfaces 202 formed thereon which are arranged to be engaged by a wedge shaped portion 204 on the forward end of a slide 206 which is mounted for reciprocating movement toward and from the shoe in a slot 208 (Fig. 9) formed in the under side of the plate 94, the slide 206 being retained in the slot by the cam 112 and by a T-shaped guideway 209 provided by a pair of gib 210 secured by screws 212 to the lower surface of the plate 94. An elongated slot 211 is formed in the slide 206 to permit it to move relatively to the projection 106 which passes through the slot in the slide. The slide 206 is provided with a downwardly extending projection 214 and, secured in a hole in this projection by a pin 216, is a horizontal rod 218 which extends rearwardly and passes through a hole in a projection 220 extending downwardly from the lower surface of a second slide 222 mounted for sliding movement in the guideway 209. Surrounding the rod 218 between the projections 214 and 220 is a compression spring 224, as shown in Fig. 9. The slide 222 is connected by a rod 226 to the cam 112. The cam 112 is provided adjacent to the projection 214 with a cam surface 228 which is eccentric relatively to the axis of the cylindrical projection 106 of the bracket 102.

It will be seen from the foregoing description that when the bracket 102 carrying the driver 122 is swung about the axis of the projection 106 from its inoperative to its operative position shown in Figs. 1 and 12, the cam 112 will be rotated in a clockwise direction, as viewed from below (Fig. 9), and the rod 226 will move the slide 222 forwardly toward the shoe. Consequently, the slide 222 will, through the yielding connections described above, move the slide 206 forwardly toward the shoe to cause the wedge shaped portion 204 to engage the curved surfaces 202 on the shoe gages 192 and separate the rear arms of the gages against the action of the spring 196 to cause the forward portions 192 to move equal distances toward the opposite sides of the shoe. The construction is such that if one gage 192 should engage the shoe before the opposite gage it will tend to move the shoe into a more centralized position until the opposite gage, which is likewise moving toward the shoe, en-

gages the opposite side of the shoe. This action, however, is a yielding action due to the yieldable connections between the slides and, accordingly, the mechanism will yield unless the heel portion 5 of the shoe is permitted by its supporting mechanism to move readily into the position determined by the shoe gages. If the shoe is not initially in a central position the operator can readily adjust the heel portion of the shoe transversely by means of the slot 32 to locate the shoe sufficiently close to its proper transverse position so that the shoe gages will engage both sides of the shoe and thereby position the shoe relatively to the operating instrumentalities. Reverse movement of the cam 112 through the rotation of the bracket 102 into its inoperative position moves the rod 226 and the slide 222 positively into its rearward or inoperative position, thereby permitting the spring 224 to expand. Since, however, the connections between the slide 222 and the forward slide 206 are not positive, this forward slide is not moved positively into its retracted position to permit the shoe gages to move outwardly away from the shoe. This movement is effected by the eccentric surface 228 on the cam 112 which is so positioned that it will engage the abutment 214 during reverse rotation of the cam and move it positively against the spring 224 into its rearward position, thereby permitting the gages to be moved away from the shoe by the spring 198. As illustrated in Fig. 3, the shoe gages 192 are provided on their shoe engaging ends with pads 230, which may be of leather, felt or similar material, to prevent the gages from scarring the shoe upper.

In practising the method of making shoes illustrated herein with the aid of the present machine, a fastening member 232 is provided for establishing the relative positions of the sole and shoe after they have been relatively positioned by the machine. This fastening member, as best shown in Fig. 10, comprises a hinge member similar to a pair of sugar tongs and having forwardly projecting legs 234, 236 the forward ends of which are provided with a plurality of sets of prongs 238 and 240 which are spaced from each other and arranged to be pressed or driven respectively into the outsole A and the bottom of the shoe B between which the hinge member is mounted before the shoe is placed in the machine. The fastening or hinge member 232 is preferably made of thin resilient material such as metal which is bent over upon itself to form the legs of the hinge. Adjacent to its rearward end the hinge member is provided with another set of prongs 242 whereby it may be readily secured to the heel seat portion of the shoe bottom. As shown in the drawings, the prongs on the hinge member may be conveniently formed by stamping them out of the metal and turning them in the proper direction away from the legs of the hinge. Preferably the prongs of each pair diverge slightly from each other to cause them to become further bent when they are driven into the work and thereby to become locked or clinched in the work.

The operator positions the hinge 232 with the rear prongs 242 extending toward the insole of the shoe B at its heel seat portion, the insole being designated in the drawings by the numeral 244. The overlasted marginal portions of the shoe upper B will, at this time, have been coated with cement 246, such, for example, as pyroxylin cement as shown in Fig. 11, and the marginal portion of the attaching surface of the outsole A

will likewise have been coated with cement 248, the cement on these parts having been allowed to dry in the usual manner. After the operator has properly positioned the hinge 232 so that the forwardly projecting legs 234, 236 extend forwardly in overlapping relation to a metal shank piece or stiffener 249 on the shoe bottom, he presses or drives the rear prongs 242 into the insole thereby securing the hinge in proper position on the shoe bottom. It will be observed in Fig. 11 that the prongs 240 on the lower leg 236 of the hinge are spaced far enough apart widthwise of the shoe so that they will not engage the metal shank piece 249 but will preferably be in positions to engage the inner portions of the overlasted margin of the shoe upper.

The operator mounts the shoe on the last pin 40 and toe rest 64, as described above, and adjusts the shoe supporting members manually until he has located them as closely as he can in the proper positions for the shoe being operated upon. The last and shoe will be capable of some further lateral adjustment because of the slide 34 and the loose fit of the last pin 40 in the last thimble 42 to permit the shoe gages to centralize the shoe exactly with the sole which is to be located thereon. The operator also adjusts the heel abutment 68, if necessary, to position the shoe longitudinally. He next places the short outsole A, provided at its rear end with the two slots 250 (Fig. 11) upon the bottom of the shoe and in approximately the proper position relatively thereto and, while holding the outsole in such position, he swings the bracket 102 and the associated mechanism, including the driver 122 and the driving lever 132 from the position shown in broken lines in Fig. 2, to the position shown in Fig. 1. This action moves the sole gage 184 forwardly over the heel seat portion of the shoe and into such position that the projections 186 thereon may be readily brought into engagement with the corresponding slots 250 in the outsole. The rear portion of the outsole B having been thus located laterally and longitudinally of the shoe bottom, the operator can readily shift the forepart of the outsole by hand until it is properly located widthwise of the shoe bottom.

While the sole gage 184 is moving into operative position, the shoe gages 192 are also moving yielding into engagement with the opposite sides of the heel portion of the shoe, this action being accomplished, as described above, by rotation of the cam 112 whereby the slide 222 is moved forwardly toward the shoe to actuate the forward slide 206 yieldingly through the spring 224 and thus to cause the wedge 204 on the latter slide to separate the rear arms of the shoe gages 192 and bring their forward ends into engagement with the shoe. The sole and shoe having been properly positioned relatively to each other, the operator depresses the treadle 164 to actuate the lever 132 and to cause the driver member 122 to descend against the outsole A and press or drive the prongs 238 and 240 on the opposite arms of the hinge 232 into the outsole and the insole 244, respectively, thereby establishing the relative positions of the rear portions of the sole and shoe widthwise and longitudinally while the sole and shoe are held in such positions by the gage members 184 and 192.

The operator then removes the sole and shoe from the machine and, as shown in Fig. 11, raises the outsole away from the shoe bottom and, by a brush 252 or similar implement, applies solvent to the cement on the inner surface of the 75

outsole A and, if desired, to that on the shoe bottom. As will be seen from Fig. 11, this operation may be easily accomplished with the aid of the hinge member 232 without losing the previously established positions of the sole and shoe. After the solvent has been applied to activate the cement the outsole A is returned to its former position on the shoe bottom and the sole and shoe are mounted in a sole attaching press 254 (Fig. 12) in which sole attaching pressure may be applied to attach the outsole permanently to the shoe bottom. As shown in Fig. 12, the sole attaching press may be of any usual type provided with last and shoe engaging abutments 256, 258 and a flexible bag or pad 260 which may be inflated through a pipe 262 to cause the sole attaching pressure to be applied. It will be noted that the sole attaching press need not be provided with sole and shoe positioning mechanism because the rear portions of the sole and shoe have already been properly positioned relatively to each other and, as indicated above, when these positions have once been established by the member 232, they are maintained without further care on the part of the operator. In placing the sole and shoe on the pad of the sole attaching press the operator will position the forepart of the sole widthwise of the shoe bottom by hand if it is not already located in proper position.

After the outsole has been permanently attached to the shoe bottom, the heel seat portion of the shoe may be prepared for the attachment of a heel in the usual manner by the application of filler material 264 (Fig. 13) and a heel 266 may be attached either by cement alone or, if desired, by cement and additional fastenings such as screws or heel attaching nails. As shown in Fig. 13, the heel is preferably a previously covered heel provided at the upper portion of its breast with a transverse groove 268 adapted to receive the rear portion of the short outsole A and conceal the slots 250 and also provide a tight joint between the heel and the outsole. The heel also has a forwardly projecting lip 270 which is arranged to overlie the rear portion of the outsole, as shown in Fig. 13. The hinge member 232 will, of course, remain in the shoe bottom but since the prongs are not long enough to extend completely through either the outsole or the insole that is no detriment to the shoe. Moreover, since the intermediate portion of the hinge member overlies the rear portion of the outsole it helps to prevent the central part of this rear portion from being stuck to the shoe bottom so that it will be free to receive the lip 270 of the heel 266.

The hinge member 232 is not claimed herein because it forms the subject-matter of a divisional application Serial No. 323,151, filed March 9, 1940, in my name. Likewise, the machine per se is not claimed herein because it constitutes the subject-matter of a divisional application Serial No. 327,881, filed April 4, 1940, in my name.

Having thus described my invention, what I claim as new and desire to secure by Letters Patent of the United States is:

1. That improvement in methods of making shoes which comprises placing a hinged fastening member between a sole and a shoe bottom, positioning the sole and shoe relatively to each other, and applying pressure to the sole and shoe to cause the hinged fastening member to penetrate into the sole and shoe bottom and thereby establish the relative positions of the sole and

shoe while permitting relative movement thereof out of said positions.

2. That improvement in methods of making shoes which comprises locating between the rear portions of a sole and a shoe bottom a fastening member adapted to permit the sole to be moved away from the shoe bottom, positioning the sole and shoe relatively to each other, and, while maintaining the relative positions of the sole and shoe, applying pressure thereto to cause the fastening member to penetrate into the sole and shoe bottom and thereby establish said relative positions prior to the direct attachment of the sole to the shoe while permitting the sole to be moved away from the shoe bottom without losing said relative positions.

3. That improvement in methods of making shoes which comprises placing a hinge member provided with oppositely extending prongs between an outsole and a shoe bottom, securing the hinge member to the shoe bottom, positioning the outsole and the shoe relatively to each other, and applying pressure to the outsole and shoe to force the prongs on the hinge member into the outsole and shoe bottom respectively, thereby establishing the relative positions of the outsole and shoe so that they may be moved relatively to each other before the permanent attachment of the outsole to the shoe without losing said established positions.

4. That improvement in methods of making shoes which comprises securing to the rear portion of a shoe bottom a hinge member provided with forwardly projecting legs having prongs thereon, placing on the shoe bottom a short outsole the rear portion of which overlies the prongs on the hinge member, positioning the outsole and shoe relatively to each other, and pressing the prongs on the hinge member into the outsole and shoe bottom respectively, thereby establishing the relative positions of the outsole and shoe and permitting relative movement of said outsole and shoe without losing said relative positions.

5. That improvement in methods of making shoes which comprises securing to the rear portion of a shoe bottom a hinge member having forwardly extending legs with prongs thereon, placing on the shoe bottom a short outsole having cement on its inner surface, the rear portion of said outsole overlying the legs of the hinge member, positioning the outsole and shoe relatively to each other, forcing the prongs on the hinge member into the outsole and shoe bottom respectively while said outsole and shoe are maintained in proper relative position thereby establishing such positions, raising the outsole with the aid of the hinge member and applying solvent to the cement on said outsole thereby activating the cement, returning the outsole to its previously established position on the shoe bottom, and applying pressure to the outsole and shoe until the cement has set, thereby permanently attaching the outsole to the shoe bottom.

6. That improvement in methods of making shoes which comprises securing to the heel seat portion of a previously cemented shoe bottom a hinge member having legs with oppositely projecting prongs on their forward ends, mounting on the shoe bottom a short outsole terminating a short distance rearwardly of the heel breast line of the shoe and having cement on its inner surface, the rear portion of said outsole overlying the prongs on the legs of said hinge member, positioning the rear portions of the outsole and shoe

relatively to each other, driving the prongs on the legs of said hinge member into the outsole and shoe bottom respectively while said outsole and shoe are held in their relative positions, thereby 5 securing the legs of the hinge member to the outsole and shoe and establishing their positions relatively to each other, raising the outsole away from the shoe bottom with the aid of said hinge member, applying solvent to the cement on the 10 outsole to activate said cement, returning the outsole to its previously established position on the shoe bottom, positioning the foreparts of the outsole and shoe bottom widthwise, applying pressure to the outsole and shoe to attach the outsole permanently to the shoe bottom, and attaching 15 a heel to the shoe adapted to interengage with the rear portion of the short outsole.

7. That improvement in methods of making shoes which comprises providing an outsole which 20 terminates in a straight edge face a short distance rearwardly of the heel breast line of a shoe and has a notch in said edge face, placing a fastening member between the outsole and the bottom of a shoe to which the outsole is to be 25 attached, said fastening member having oppositely extending prongs thereon arranged to penetrate into the outsole and shoe bottom, positioning the outsole relatively to the shoe bottom by engaging said notch and the opposite sides of the 30 shoe, applying pressure to the shoe and outsole while thus positioned to force said prongs to penetrate into the shoe bottom and the outsole and thereby establish the relative positions of said outsole and shoe so that they may be re-established 35 without again engaging said notch and the opposite sides of the shoe, and, after releasing said engagements with the outsole and shoe, cement

attaching the outsole to the shoe by applying pressure thereto.

8. That improvement in methods of making shoes which comprises providing an outsole which extends only a short distance rearwardly of the 5 heel breast line of a shoe and has a straight rear edge face with a plurality of notches therein, applying cement to the attaching surface of said outsole, securing to the heel seat portion of a shoe bottom a hinged fastening member having 10 forwardly extending legs with oppositely projecting prongs on their forward ends arranged to penetrate into the outsole and the shoe bottom, placing the outsole on the shoe bottom with the rear portion of the outsole overlapping the forward ends of the legs of said fastening member, positioning the outsole and shoe relatively to each other by engaging the opposite sides of the shoe and the notches in the rear edge face of the outsole, applying pressure to the outsole and shoe 20 while they are maintained in such positions to cause the prongs on said fastening member to penetrate into the rear portion of the outsole and the shoe bottom respectively, thereby establishing their relative positions prior to the attachment 25 of the outsole to the shoe and enabling said positions to be re-established without again engaging the shoe and the notches in the outsole, releasing the engagements with the outsole and shoe and activating the cement on the outsole after lifting 30 the outsole away from the shoe bottom with the aid of the hinged fastening member, returning the outsole to its pre-established position on the shoe bottom by means of said fastening member, and applying pressure to the shoe and outsole to 35 cement attach the outsole to the shoe bottom.

NAPOLEON A. MONFILS.
